(57) **CLAIM**

The ornamental design for a combined cosmetic puff and sponge, as shown and described.

DESCRIPTION

FIG. 1 is a perspective view from a top side view of a combined cosmetic puff and sponge showing my new design;

FIG. 2 is a perspective view of a bottom side view thereof;

FIG. 3 is a rear view thereof;

FIG. 4 is a front view thereof;

FIG. 5 is a left view thereof;

FIG. 6 is a top view thereof; and,

FIG. 7 is a bottom view thereof.

The broken lines represent stitching that forms part of the claimed design.
